UNITED STATES PATENT OFFICE

ORTON L. BEVERLY, OF INDIANAPOLIS, INDIANA

DEVICE FOR PREVENTING SAFE ROBBERIES

Application filed February 23, 1928. Serial No. 256,197.

This invention relates to those devices for preventing safe robberies wherein the tampering with the safe liberates a noxious gas. The burglar almost invariably makes his attack by breaking off the knob of the combination lock dial by hammer blows and then further damaging the lock by driving in the pin which carried the knob before the knob was broken off. Gas releasing devices have been installed which operated by the driving in of the pin, and the object of this invention is to provide means for discharging of the gas from the safe as soon as the knob, and its dial which is integral with it, are knocked off by the burglar, and before he has damaged the lock by driving in the dial pin. I accomplish the above, and other objects which will hereinafter appear, by the mechanism illustrated in the accompanying drawings, in which—

Fig. 1, is a front elevation of a safe dial and adjacent portions of the safe door, the dial being broken away in part.

Fig. 2, is a horizontal section on the line 2—2 of Fig. 1.

Fig. 3, is a view in elevation of a portion of the inside of a safe door showing the tube of my device in part vertical section.

Fig. 4, is a detail in vertical section on the line 4—4 of Fig. 3.

Fig. 5, is an elevation of a modified structure looking toward the inside of the door, and

Fig. 6, is a horizontal section on the line 6—6 of Fig. 5.

Like characters of reference indicate like parts in the several views.

A safe door 7, is equipped with the usual permutation lock 8 which is operated by a pin or shaft 9 having an anchorage on its inner end and having a dial plate 10, located on the outside of the door, attached to its outer end by any suitable means as by a pin 11. The dial plate has an outside knob 12 by which the plate and shaft 9 are rotated. A plate 13, recessed on its outer face to receive the dial plate, is fixed to the face of the door. It usually has cut away openings 14 to save metal and has a central annular flange 15 receiving a hub on the dial plate.

Fixed to the inside of the door is a vertical sleeve 16, by which a metal tube 17 is supported.

The interior of the lower end of the tube 17 is screw threaded and receives the threaded end of a tube 18 of a container or grenade 19 of usual content and construction having a detonator (not shown) which is set off by a striker 20, located in the tube 17. The grenade 19 contains a suitable gas producing substance and a combustible for gasifying it, such as chloracetophenone crystals and gun powder, not shown. A dowel pin 21 is passed through suitable openings in the tube 18 and striker 20 to prevent accidental discharge of the grenade until the device is set ready for use, when the pin is removed.

Located in the tube 17 is a reciprocating plunger 22 which is adapted, upon release, to contact the striker 20 and explode the detonator in the grenade. This plunger is held during transportation, and assembly of the device in a safe, by a screw bolt 23 which passes through a cap 24 of the tube 17 and is screwed into the end of the plunger after which it is removed. A spirally wound spring 25 exerts a normal downward pressure against the plunger. The plunger is held in raised position, away from the striker 20 by a horizontal plunger lock flange 26 on a plate 27. The plate 27 is hinged at one end to a flange-extension 28 from the plate-supporting sleeve 16. The tube 17 is slotted opposite the lower end of the plunger 22 in raised position of the plunger for the passage therethrough of the flange 26 under the raised plunger to hold the plunger up and out of contact with the striker, except when the safe-lock is being improperly tampered with.

The mechanism for retaining the plate 27 with its flange in position to hold the plunger up, comprises a link bar 30 having an eye at each end, and attached by an eye at one end to that end of the plate 27 which is remote from the hinge end of said plate. The link bar 30 passes thence through a hole, previously drilled for that purpose through the safe-door, and is connected by its other eye with the end of a lever 32 placed radially of the dial plate, and having its free end held

in a notch in the flange 15 of the plate 13, where it is retained until released by the removal of the dial plate, as when broken off by a burglar. The dial plate rotates freely over the end of the lever 32 in the normal manipulation of the safe-lock.

The plate 27, link bar 30, and radial lever 32 are held in taut position by a spring 33, located between the plate 27 and an extension 34 of the support for sleeve 16. The spring is positioned by a pin 36.

If necessary, the hole through the door may be lined by a tube 37. This hole allows for the passage of link bar 30 and also for the prompt escape of the incapacitating gas generated in the grenade following an explosion of its detonator after the dial-plate has been knocked off. The gas also escapes around the door in the usual manner.

Inasmuch as the metal from which some safe-doors are made is too hard to be drilled in applying my invention, I attach an arm 38 to the back plate of the lock case, and extend it into contact with the plate 27', so that when the dowel shaft is driven in the arm 38 will go with the lock, thereby releasing the plate 27'. This modification is clearly illustrated in Figs. 5 and 6.

While I have here shown and described the best form of my invention now known to me it is capable of modifications without departing from the spirit of the invention and I do not desire to be limited any more than is required by the appended claims.

I claim:

1. A device for preventing safe robberies and the like, comprising a dial plate, a grenade containing incapacitating gas producing materials, a striker, a plunger to operate the striker, and means cooperating with the dial plate for holding the plunger out of operative contact with the striker while the dial plate is in normal position and for releasing the plunger by the removal of the dial plate from normal position.

2. A device for preventing safe robberies and the like, comprising a dial plate, a grenade containing incapacitating gas producing materials, a striker, a plunger to operate the striker, a lever located in the dial plate and means cooperating with the lever for holding the plunger out of operative contact with the striker while the dial plate is in normal position and for releasing the plunger immediately upon the removal of the dial plate from normal position.

3. A device for preventing safe robberies and the like, comprising a dial plate, a grenade having incapacitating gas producing materials, and means for liberating gas from the grenade held inoperative by the dial plate and operative by removal of the dial plate.

4. A device for preventing safe robberies and the like, comprising a dial plate, a grenade containing incapacitating gas produc-

ing materials, a striker, a plunger, a plunger-lock flange, and a lever connected with the plunger-lock flange to lock the plunger in one position of the lever, said lever being held in plunger-locking position by the dial plate and released by the removal of the dial plate.

5. A device for preventing safe robberies and the like, comprising a dial plate, a grenade containing incapacitating gas producing materials, a striker, a plunger, a plunger-lock flange, a lever connected with the plunger-lock flange to lock the plunger in one position of the lever, said lever being held in plunger-locking position by the dial plate and released by the removal of the dial plate and a spring means to quicken the release of the plunger when the dial plate is removed.

6. A device for preventing safe robberies and the like, comprising a dial plate, a grenade containing incapacitating gas-producing materials, a striker, a plunger, a swinging member having a projection engaging and locking the plunger out of contact with the striker, a lever, and a link connecting the free end of the swinging member with one end of the lever, and the other end of the lever being held by the dial plate in position of its connected parts to lock the plunger away from the striker until released by the removal of the dial plate.

7. In a device for preventing safe robberies and the like, a safe having a door, a dial plate located on the outside of the safe door, said door having a hole through it near the edge of the dial plate, and a lever having one end at the hole and its other end held by the dial plate, in combination with a link means connected with the lever and extending to the inside of the safe through the hole in the door, a grenade containing incapacitating gas-producing materials, a striker, a plunger, a swinging member having a plunger-lock flange the free end of said swinging member being attached to the link means all located within the safe, and spring means to hasten the action of the parts upon release of the lever by the removal of the dial plate.

8. A device for preventing safe robberies and the like comprising a dial plate, a container holding incapacitating gas producing materials, means to act on the grenade and liberate said materials to form gas, and means cooperating with the dial plate to operate the last means only when the dial plate is removed from the safe.

9. A device for preventing safe robberies and the like comprising a dial plate, a container having incapacitating gas producing materials, means comprising a reciprocating member to act on the grenade and liberate said materials to form gas, and means comprising a lever cooperating with the dial

plate to operate the last means only when the dial plate is removed from the safe.

10. A device for preventing safe robberies and the like comprising a dial plate, a container charged with incapacitating gas producing materials, means comprising a reciprocating member and a flange to hold the member inoperative adapted to operate on the grenade and liberate said materials to form gas, and means to release the flange, comprising a lever held by the dial plate and released to operate the catch by the removal of the dial plate from the safe.

In testimony whereof I affix my signature.
